US0D1031035S

(12) **United States Design Patent** (10) **Patent No.:** **US D1,031,035 S**
(45) **Date of Patent:** **** Jun. 11, 2024**

(54) **ENDOSCOPE HANDLE**

(71) Applicant: **AdaptivEndo LLC**, Louisville, KY (US)

(72) Inventor: **Michael W. Goldenbogen**, Xenia, OH (US)

(73) Assignee: **AdaptivEndo LLC**, Louisville, KY (US)

(**) Term: **15 Years**

(21) Appl. No.: **29/781,304**

(22) Filed: **Apr. 29, 2021**

(51) LOC (14) Cl. **24-02**

(52) U.S. Cl.

USPC **D24/138**

(58) **Field of Classification Search**

CLAIM

The ornamental design for an endoscope handle, as shown and described.

DESCRIPTION

FIG. 1 is a front, right, perspective view showing my new design in a first embodiment;

FIG. 2 is a back, left perspective view thereof;

FIG. 3 is a left side view thereof;

FIG. 4 is a back side view thereof;

FIG. 5 is a right side view thereof;

FIG. 6 is a front view thereof;

FIG. 7 is a top view thereof;

FIG. 8 is a bottom view thereof;

FIG. 9 is a front, right, perspective view showing my new design in a second embodiment;

FIG. 10 is a back, left perspective view thereof;

FIG. 11 is a left side view thereof;

FIG. 12 is a back side view thereof;

FIG. 13 is a right side view thereof;

FIG. 14 is a front view thereof;

FIG. 15 is a top view thereof; and,

FIG. 16 is a bottom view thereof.

The broken lines depict portions of the endoscope handle that form no part of the claimed design.

1 Claim, 16 Drawing Sheets
